UNITED STATES PATENT OFFICE.

GEORGE H. BASS, OF WILTON, MAINE.

MOCCASIN.

984,739.

Specification of Letters Patent. Patented Feb. 21, 1911.

Application filed April 19, 1910. Serial No. 556,427.

To all whom it may concern:

Be it known that I, GEORGE H. BASS, a citizen of the United States, residing at Wilton, in the county of Franklin and State 5 of Maine, have invented certain new and useful Improvements in Moccasins, of which the following is a specification.

My invention relates to soft leather shoes or slippers known as moccasins, the sole and 10 upper of which are in one piece. As commonly made, a moccasin is a limp, loose-fitting shoe, and lacks shapeliness especially at the shank or the arch of the foot where the upper tends to bulge out or run over at 15 the sides.

The object of my invention is to obviate this defect, and improve the construction of moccasins with a view to obtaining a better fit and appearance, and a more practicable 20 lasting and comfortable wearing shoe.

The invention will be described with reference to the accompanying drawings and be pointed out more particularly in the claim appended to this specification.

25 In said drawings, Figure 1 is a perspective view of a moccasin embodying my invention, the near side being broken away to reveal the interior. Fig. 2 is a plan view of the blank from which the sole and upper 30 are made. Fig. 3 is a back view of the heel. Fig. 4 is a perspective view similar to Fig. 1, showing a modification. Fig. 5 is a plan view of the blank for the sole and upper of the moccasin shown in Fig. 4.

35 To facilitate the description, parts of the moccasin may be designated as follows: 1 is the sole portion; 2 is the top portion formed to provide the tongue 3; 4 is the ball-and-toe portion of the upper, which is sewn to the 40 top portion 2 with an outstanding seam 5; and 6 is the back portion of the vamp or upper including the heel or counter portion 7 and also including the lacing flaps 8. The sole portion 1 of the moccasin is extended to 45 form the upper including the ball-and-toe portion 4 thereof and which is sewn to the top portion 2 as in the usual construction. 9 is the shank or that portion of the shoe at the arch of the foot.

50 Referring to Figs. 1 and 2, the piece for the sole and upper is made from two blanks *a* and *b*, symmetrical with respect to one another and having the proper marginal contour for the upper, including the ball-and-toe portion 4 and the rear portion 6 with its 55 lacing flaps as shown. The inner edges of

the blanks are sewn together, making a longitudinal seam 10 along the middle of the sole.

In Fig. 2, *d* indicates the point on the sole 60 where it turns up at the toe; *e* is a point just back of the ball of the foot and *f* is a point under the ball of the heel. The inner edges of the blanks diverge from *d* to *c*. From *d* to *e* the edges are straight or parallel, but 65 from *e* to *f* they are cut away on a concave, as indicated at *g*, which of course leaves a space between them when the blanks are adjoined. Hence when the edges from *d* to *f* are stitched together with a 70 straight seam the effect is to contract and partially gather the shank portions *h* of the blanks. The back portions of the blanks are cut away as indicated at *i* and are slit at 75 *j*, to allow the leather to spread so as to adjust itself to the round part of the heel, leaving an opening which is covered by the sole on the outside and may be covered by a piece of sole leather over the heel seat on the inside. The advantage of making the 80 moccasin this way is that it will fit the last in the shank so that it will be much more comfortable and shapely, and it also gives an opportunity to put in a stiffener or counter 85 12 of sole leather at the heel, and to make the heel seam 13 as in an ordinary shoe. Making the sole and upper from the two blanks is also conducive to economy of material, since it enables the manufacturer to utilize smaller pieces of leather. 90

In making the moccasin, the blanks *a* and *b* are first stitched together with a machine, making a straight seam from *d* to *f*. The edges may also be stitched together from *d* to *c*, but are preferably stitched to a toe 95 piece 14. The counter or heel stiffener 12 is then put in and a bottom sole or outsole 15 of ordinary sole leather is fastened on, before the moccasin goes to the last. It is then lasted, and the top piece 2 is afterward 100 sewn in by hand in the ordinary moccasin fashion. The product is a real moccasin with the addition of sole and counter, and has the advantage of giving a much better fit. 105

Referring to Figs. 4 and 5, the sole and upper of the moccasin therein represented are made from a single blank *k*, which corresponds to the two blanks *a* and *b* of Fig. 2 if sewn together from *d* to *e* but without the gap from *c* to *d*. This single blank *k* has a portion removed or cut away along its 110

longitudinal middle from *e* to *f* leaving the concave edges *g g* in the same manner and for the like purpose as in Fig. 2. The rear portion is cut away at *i* and slitted at *j* as 5 in the previous construction. Otherwise the construction of the moccasin is the same, omitting the toe piece 14 of Fig. 1.

In the following claim, the term "upper" is intended to designate the vamp or upper 10 including the rear portion 6 and ball-and-toe portion 4, but not including the top portion 2. The expression "blank for the sole and upper" is intended to include the blanks shown in Fig. 2 or the single blank shown in 15 Fig. 5.

I claim as my invention and desire to secure by Letters Patent:

A moccasin consisting of the top portion

2 and blank for the sole and upper, the ball-and-toe portion of which is sewn to the said 20 top portion, the said blank having the longitudinal cut away portion *e f* with its concave edges *g* stitched together along a medial sole seam and having the rear cut away portion *i* and slit *j*, together with the 25 heel stiffener or counter 12 and under sole 15, the back ends of the blank being stitched along the heel seam 13 substantially as described.

In testimony whereof I affix my signature, 30 in presence of two witnesses.

GEORGE H. BASS.
